UNITED STATES PATENT OFFICE.

LOUIS W. REINHARDT, OF BROCKTON, MASSACHUSETTS, ASSIGNOR TO GEORGE E. BELCHER LAST COMPANY, OF STOUGHTON, MASSACHUSETTS, A CORPORATION OF MASSACHUSETTS.

SHOE-FORM.

1,023,395.

Specification of Letters Patent.

Patented Apr. 16, 1912.

Application filed October 12, 1911. Serial No. 654,266.

To all whom it may concern:

Be it known that I, LOUIS W. REINHARDT, a citizen of the United States, and resident of Brockton, county of Plymouth, State of 5 Massachusetts, have invented an Improvement in Shoe-Forms, of which the following description, in connection with the accompanying drawing, is a specification, like characters on the drawing representing like 10 parts.

This invention relates to a shoe form for shoes, and its object is to provide a device of this character which will be of simple but strong construction, and which shall hold 15 the shoe in its proper shape, supporting and keeping the upper smooth throughout. Shoe forms of this character are used principally in displaying shoes for sale, and are largely carried by traveling salesmen. It is essential, therefore, that the shoe form should 20 be as light as possible, and that it should display the shoe in the most attractive and artistic manner, and that it should be itself pleasing in appearance to the eye.

25 The present invention presents a device made of thin material, such as fiber board, and which consequently is of light weight. It is so constructed that when in position in the shoe it firmly supports the fore part 30 of the shoe and braces the heel part so as to maintain the upper edge of the shoe in proper position. At the same time it is formed to cover the interior of the shoe, hiding the mechanism of the form, and affording a place for the display of the name 35 or advertisement of the manufacturer or dealer.

The nature of the invention will more 40 fully appear from the accompanying description and drawings, and will be particularly pointed out in the appended claims.

The drawings show the invention in its preferred form, and applied to an ordinary style of low cut or Oxford shoe.

45 In the drawings, Figure 1 represents in perspective a shoe with the form of this invention in place therein, and indicated in dotted lines. Fig. 2 is a vertical cross section of the shoe and form taken on the line 50 $x-x$ of Fig. 3, the dotted lines indicating the position of the form parts when about to be removed from the shoe. Fig. 3 is a bottom plan view of the form.

The form of this invention may be made 55 of any suitable thin material capable of be-

ing given the desired shape, and having sufficient strength. It is preferably made of fiber board formed into the desired shape.

The shoe form comprises three main elements, viz., the fore part, the cover part 60 and the hinge member. The fore part is shown at 1 and consists of a thin hollow shell of the material such as fiber board, the exterior surface of the shell conforming to the interior of the fore part of the shoe, and 65 having in effect the same configuration as the last upon which the shoe was made, so that this part of the shoe may be supported in its normal and correct shape. This fore part rests on the sole of the shoe, and is 70 preferably split longitudinally throughout at the bottom, as may be seen from Fig. 3, this being there shown as caused by the removal of all the bottom portion of the form excepting a flange 2 at each side. Means are 75 provided for expanding the shell so that when placed within the fore part of the shoe it may be pressed into normal position. Such means are herein illustrated as a toggle joint comprising the link 3 pivoted to 80 one side of the shell and pivoted to the link 4, which in turn is pivoted to the opposite side of the shell. The link 4 is provided with a finger piece 5 by means of which the toggle joint can be opened and closed. 85

The cover part of the shoe form is preferably made of the same material as the fore part, and is indicated at 6. It comprises a curved top 7 and a depending peripheral flange 8, the latter conforming to 90 the inner surface of the shoe upper. This flange at its forward portion conforms to and fits snugly against and preferably over the upper edge of the fore part, and the flange is skived at its lower edge to enable 95 it to lie against the fore part without making an objectionable ridge.

The hinge member by which the fore part and cover part are connected is preferably formed of a U-shaped strip of metal, the 100 legs 9 and 10 of which are respectively pivoted at their free ends to the lower rear side portions of the fore part. The curved center portion of the hinge member, when the cover part is in normal position, abuts 105 against the rear portion of the depending flange thereof and presses the same firmly against the rear portion of the shoe upper and adjacent the upper edge of the heel counter, so that the shoe upper is stretched 110

slightly to cause it to cling firmly to the cover part of the form, and maintain its proper shape. The hinge member is pivoted intermediate the ends of its legs to the 5 depending flange 8 of the cover part at each side, as indicated at 11 and 12, and the hinge member when the form is in position extends upwardly in inclined direction.

The construction and operation of the 10 shoe form will be apparent from the foregoing description. To insert the form the toe part is slipped into the shoe with the toggle joint 5 open. The toggle joint is then closed by reaching into the shoe. The 15 cover part is then swung downwardly as indicated in dotted lines in Fig. 2, and pressed into the shoe until the rear end engages the rear portion of the shoe upper. Then upon pressing the cover down into 20 place the hinge member acts as a sort of toggle joint, stretching the shoe upper lengthwise, and when the cover part comes into final position with its flange fitting over and resting against the upper rear 25 edge of the fore part, the hinge member extends in an inclined direction from the lower rear end of the fore part upwardly to the rear portion of the shoe upper near the top of the heel counter, locking the parts of 30 the shoe form in place and bracing the shoe longitudinally, and thus causing the shoe upper to cling to the form.

The form is shown in place in Fig. 2, and it will be seen that the cover part conceals 35 the interior mechanism of the form, and presents a place upon which the name or advertisement of the manufacturer or dealer may be placed.

The invention having been fully de- 40 scribed, what is claimed as new and desired to be secured by Letters Patent, is:

1. A shoe form comprising a fore part, a 45 cover part having its periphery conforming to the shape of the shoe upper, and a hinge member pivoted at one end to the lower

rear end of the fore part and pivoted at an intermediate point to the rear portion of the cover part, and when the shoe form is in position bracing the rear edge of the cover part against the rear of the shoe upper to 50 cause the shoe upper to fit against and conform to the edge of the cover part.

2. A shoe form comprising a fore part conforming to the shape of the fore part of the shoe, a cover part having a depending 55 peripheral flange conforming to the shoe upper and fitting against the upper rear edge of the fore part, and a U-shaped hinge member pivoted at the ends of its legs to said fore part, and pivoted at intermediate 60 points of its legs to the flange of the cover part, and having its curved center portion when the form is in position bracing the rear of the shoe upper near the top of the heel counter.

3. A shoe form comprising a fore part, a cover part and a U-shaped hinge member, the said fore part being a thin hollow shell of suitable material conforming to the fore part of the shoe, split longitudinally at the 70 bottom and provided with means for expanding it laterally, the said cover part having a depending peripheral flange conforming to the shape of the shoe upper and fitting over the upper rear edge of the fore part and the said hinge member being pivoted at the ends of its legs to the sides of the fore part near the lower rear edges and being pivoted intermediate of its legs to the depending flange of the cover part near the 75 rear thereof, and when the form is in position having its center portion braced against the rear of the shoe upper.

In testimony whereof, I have signed my name to this specification in the presence of 80 two subscribing witnesses.

LOUIS W. REINHARDT.
